UNITED STATES PATENT OFFICE.

JOHN KELLY, OF JAMAICA PLAIN, MASSACHUSETTS.

EXCAVATING-CONVEYER.

983,906.

Specification of Letters Patent. Patented Feb. 14, 1911.

Application filed February 17, 1910. Serial No. 544,356.

To all whom it may concern:

Be it known that I, JOHN KELLY, a citizen of the United States, residing at Jamaica Plain, in the county of Suffolk and State of Massachusetts, have invented new and useful Improvements in Excavating-Conveyers, of which the following is a specification.

This invention relates to improvements in excavating and elevating apparatus, and the object is to provide a portable apparatus of this class which shall be particularly adapted for use in excavating collections of matter from sewer catch basins and the like and depositing such matter in a suitable receptacle forming a part of the apparatus.

The object is further to provide suitable means for raising and lowering the excavator to move the same into and out of catch basins.

A still further object is to provide a movable lateral wall which constitutes a tail-board for the vehicle box and means for operating the same to discharge the contents of said box.

The invention consists in the novel features of construction and in the combination and arrangement of parts set forth in the following specification and particularly pointed out in the claims.

Referring to the drawings: Figure 1 is a side elevation, partly in section, of an apparatus embodying my invention. Fig. 2 is a diagrammatic view showing the apparatus as the same is arranged when operating in a catch basin or the like. Fig. 3 is a plan of the apparatus. Fig. 4 is an elevation of the apparatus viewed from the left hand side of Fig. 3. Fig. 5 is a sectional view taken on line 5—5 of Fig. 3. Fig. 6 is a sectional view taken on line 6—6 of Fig. 5.

Like numerals refer to like parts throughout the several views of the drawings.

In the drawings, 10 is a box on which is supported an endless link belt conveyer 11 having an approximately horizontal portion 12 and an approximately vertical portion 13 and consisting preferably of a pair of chains having suitable buckets 14 mounted thereon at suitable intervals. The horizontal portion 12 of the conveyer is located above the box 10 so as to discharge thereinto and said box is provided with a suitable tail-board 15 which is constructed and adapted to be opened as hereinafter described to discharge the contents of said box. The vertical portion 13 at its lower terminal portion extends

around a pair of sprocket wheels 16 journaled on a shaft 17 terminating at its opposite ends in vertical rods 18 constituting slides mounted, respectively, in guides 19. The guides 19 are secured to a shaft 20 pivotally mounted in bearing brackets 21 secured to the rear end of the box 10 and on this shaft two sprocket wheels 22 are journaled.

The tail-board 15 is pivotally mounted on a shaft 23 on which two sprocket wheels 24 are mounted to rotate about the axis of said shaft. The chains of the conveyer 12 pass around the sprocket wheels 16 and upwardly around the sprocket wheels 22 and 24 and extend thence approximately horizontally toward the front of the box 10, the terminal portions of said chains passing around sprocket wheels 25 secured to a shaft 26. The shaft 26 is journaled in suitable bearings 27 constituting slides which are mounted to slide, respectively, in suitable guides 28 mounted on the box 10 on opposite sides of the conveyer belt.

Mounted on opposite ends, respectively, of the shaft 26 are two drums 29 around which are wound flexible members 30 consisting of endless ropes or chains, these ropes passing around idler drums 31 journaled, respectively, on studs 32 secured to the guides 28, respectively, said ropes extending also around drums 33, respectively, secured to a driving shaft 34 journaled in suitable bearings 35 on the front of the box 10. It will be understood that only the upper portion of each of the endless ropes 30 is wound around its respective drum 29 and it will be understood that each rope is wound around such drum one or more times so that when a longitudinal movement is imparted to said ropes, said drums are rotated, thereby rotating the sprocket wheels 25 and driving the conveyer belt 12, the normal direction of travel of which is indicated by the arrow A, Fig. 1.

Preferably, the apparatus is mounted upon a motor vehicle, as shown, so that the same may be transported from one place to another. The motor vehicle is provided with usual traction wheels 36 driven in any usual or desired manner by an engine 37 through a suitable clutch 38 and transmission mechanism 39 and this engine serves as a convenient source of power for driving the conveyer, the transmission mechanism being connected to the conveyer by a sprocket

wheel 40, a chain 41 and a sprocket wheel 42 secured to the driving shaft 34. The bearings 27 are connected to each other by a yoke 43 to which is connected a suitable means for controlling the movement of said bearings in their respective slides, such means in this instance, consisting of a tackle 44 comprising a rope 45 passing through suitable sheaves in a block 46 mounted on the yoke 43 and passing through suitable sheaves in a block 47 mounted on any suitable fixed means, such as a post 48. This tackle serves not only as a means for restraining the bearings 27 of the shaft 26 as to movement toward the rear of the apparatus, but may also be employed to move said bearings and shaft toward the front of the apparatus. In practice, the weight of the vertical portion 13 of the conveyer belt 20 and the slides 18 will be sufficient to tend to carry the same downwardly if released by the tackle just described.

Secured to the upper ends of the rods 18 is a yoke 49 which is connected to the post 48 by a tackle consisting of a rope 50 passing through sheaves in a pulley block 51 connected to said yoke and a pulley block 52 connected to said posts, whereby said rods may be rocked about the axis of the shaft 20. The rods 18 may be connected to the tail-board 15 by any suitable detachable connection or connections such as chains 53, whereby by rocking said rods about the shaft 20, the pivoted tail-board 15 may be swung outwardly toward the rear to discharge the contents of the box 10. These chains may be disconnected from the rods 18 when the apparatus is in operation.

The tail-board 15 is normally locked in its closed position by means of two bolts 54 operated by levers 55 pivotally connected to each other and pivotally mounted on said tail-board, said levers constituting a toggle connected by a link 56 to a manually operable lever 57 by means of which said bolts may be actuated to unlock the tail-board.

Secured to the shaft 26 are two ratchets 58 engaged by pawls 59, respectively, pivoted on the bearings 27, said pawls and ratchets serving to lock said shaft against clockwise movement, see Fig. 6, but permitting said shaft and the sprocket wheels 25 thereon to be rotated counterclockwise. Thus it will be understood that if the chain 41 be driven in the direction of the arrow B, Fig. 1, the endless ropes 30 will act through the drums 29 to impart a counterclockwise rotation to the shaft 26 and the sprocket wheels 25, thereby driving the conveyer belt in the direction of the arrow A. If, however, the direction of travel of the chain 41 be reversed, the pawls 59 coöperating with the ratchets 58 will act to lock the shaft 26 and sprocket wheels 25 against clockwise rotative movement, the consequence being that

the upper portions of the ropes 30 will be driven in the direction of the arrow C, Fig. 1, thereby carrying the shaft 26, bearings 27, sprocket wheels 25 and the horizontal portion of the conveyer connected thereto toward the right, thus lifting the vertical portion of the conveyer.

The general operation of the apparatus hereinbefore specifically described is as follows: The apparatus travels under its own power from place to place and when it is desired to operate the same to clean out a catch basin or for any other excavating work, the apparatus is placed in proper position with relation thereto, as for example, as shown in Fig. 2. The chains 53 are disconnected from the rods 18 and the conveyer is connected to be driven by the engine 37 in the direction of the arrow A, Fig. 1. The rope 45 is then operated to allow the vertical portion of the conveyer to move downwardly and the shaft 26 and sprocket wheels 25 to move toward the left from the position shown in Fig. 1 to the position shown in Fig. 2, it being understood that the conveyer will be constantly driven by the ropes 30 by reason of their connection with the drums 29. As the conveyer is thus driven, the buckets 14 pick up the mud or other matter, carry the same upwardly and deposit it in the box 10, it being understood that the rope 45 will be operated to allow the vertical portion of the conveyer to gradually descend until the bottom of the catch basin is reached. When the work is completed, the conveyer is raised by reversing the direction of travel of the chain 41, whereby the pawls 59 coöperating with the ratchets 58 act to lock the shaft 26 and sprocket wheels 25 against clockwise rotation, as a consequence of which the horizontal portion of the conveyer is carried toward the right and the vertical portion of the conveyer is lifted until the parts occupy their normal positions, whereupon the clutch 38 is disengaged, thus bringing the parts to a state of rest in their normal positions, as shown in Fig. 1. The load of material thus collected is transported to the place where it is to be dumped and when backed up to the proper point, the tail-board 15 is swung open, as hereinbefore described, by operating the rope 50.

Having thus described my invention, what I claim and desire by Letters Patent to secure is:

1. An apparatus of the class described having, in combination, an endless belt conveyer having a vertically disposed portion and a horizontally disposed portion, a driving wheel engaging said horizontally disposed portion, a drum connected to said driving wheel, an endless flexible member wound about said drum and having two portions extending horizontally in opposite

directions, respectively, from said drum, means to impart a longitudinal movement to said member, and a pawl and ratchet connected to said drum and operating to hold 5 the same against rotative movement in one direction.

2. An apparatus of the class described having, in combination, an endless belt conveyer having a vertically disposed portion 10 and a horizontally disposed portion, a wheel around which said vertically disposed portion passes at its lower termination, a slide on which said wheel is journaled, a guide on which said slide is mounted, a pivot on which said guide is mounted to rock, a receptacle located beneath 15 said horizontally disposed portion and having a horizontally pivoted lateral wall connected to said slide to be operated thereby, and means connected to said horizontally disposed portion to move the same bodily horizontally in the direction of its 20 length, thereby to move said vertically disposed portion vertically.

25 3. An apparatus of the class described having, in combination, an endless belt conveyer having a vertically disposed portion and a horizontally disposed portion, a wheel around which said vertically disposed portion passes at its lower termination, a slide on which said wheel is journaled, a guide on which said slide is mounted, a pivot on which said guide is mounted to rock, means to rock said guide on said pivot, a receptacle located beneath said horizontally disposed portion and having a horizontally pivoted lateral wall connected to said slide to be operated thereby, and means connected to said horizontally disposed portion to 30 move the same bodily horizontally in the direction of its length, thereby to move said vertically disposed portion vertically.

4. An apparatus of the class described having, in combination, an endless conveyer belt, a driving wheel engaging said belt, a 45

bearing for said wheel, a guide for said bearing, a drum connected to said driving wheel, an endless flexible member wound about said drum and having two portions extending horizontally in opposite directions, respectively, from said drum, means to impart a longitudinal movement to said member, and means on said bearing to hold 50 said drum against rotative movement in one direction. 55

5. An apparatus of the class described having, in combination, an endless conveyer belt, a driving wheel engaging said belt, a bearing for said wheel, a guide for said bearing, a drum connected to said driving 60 wheel, an endless flexible member wound about said drum and having two portions extending horizontally in opposite directions, respectively, from said drum, means to impart a longitudinal movement to said 65 member, a pawl mounted on said bearing, and a co-acting ratchet connected to said driving wheel.

6. An apparatus of the class described having, in combination, an endless conveyer 70 belt, a driving wheel engaging said belt, a bearing for said wheel, a guide for said bearing, a drum connected to said driving wheel, an endless flexible member wound about said drum and having two portions 75 extending horizontally in opposite directions, respectively, from said drum, means to impart a longitudinal movement to said member, and means secured to said bearing permitting rotation of said drum in one direction, but preventing rotation thereof in the opposite direction. 80

In testimony whereof I have hereunto set my hand in presence of two subscribing witnesses.

JOHN KELLY.
